UNITED STATES PATENT OFFICE.

LEONARD R. BRUNSWICK, OF SUPERIOR, WISCONSIN.

ELECTRICAL BOILER.

1,378,761.

Specification of Letters Patent. Patented May 17, 1921.

Application filed September 22, 1920. Serial No. 412,044.

To all whom it may concern:

Be it known that I, LEONARD R. BRUNSWICK, a citizen of the United States, residing at Superior, in the county of Douglas and 5 State of Wisconsin, have invented certain new and useful Improvements in Electrical Boilers, of which the following is a specification, reference being had to the accompanying drawings.

10 This invention relates to electrical boilers.

An important object of the invention is to provide a device of this character which may be employed in connection with the heating plants of houses.

15 A further object of the invention is to provide a novel heating boiler for this purpose.

A still further object is to provide in such a boiler removable heating units of simple 20 and efficient construction.

Other objects and advantages of the invention will become apparent throughout the course of the following description.

In the accompanying drawings wherein 25 for the purpose of illustration is shown a preferred embodiment of my invention, and wherein like reference characters designate like parts throughout:

Figure 1 is a side elevation partly in section of an electrical boiler constructed in accordance with my invention;

Fig. 2 is a transverse sectional view taken therethrough, the heating units and tubes being removed;

30 Fig. 3 is a longitudinal sectional view taken through the heating tube and unit of my boiler, partly shown in elevation for the purpose of illustration;

Fig. 4 is a section on the line 4—4 of 40 Fig. 3;

Fig. 5 is a section on the line 5—5 of Fig. 3, and

Fig. 6 is a section on the line 6—6 of Fig. 3.

45 Referring now more particularly to the drawings, the boiler is composed of inner and outer shells 10 and 11, spaced by non-conducting spacing elements 13. At the lower side of the boiler an inlet 14 extends

50 through both inner and outer shells and communicates with the interior of the boiler and at the upper side thereof an outlet 15 extends through the shells and communicates with the interior of the boiler. The 55 inlet 14 and outlet 15 are preferably ar-

ranged at opposite ends of the boiler. Each end of the boiler is closed by a continuation of the side walls 10 and 11, one of these ends having the spaced walls 10^a and 11^a thereof provided with vertically spaced 60 transverse rows of openings extending through both inner and outer walls. At spaced intervals within the boiler are arranged spacing plates 21, having suitable means for securing them to the inner wall 65 of the boiler. These plates are provided with openings similarly arranged to the openings 20 formed in the end wall.

Tubes 22, having their inner ends closed, extend through the alined openings in the 70 end walls and spacing plates 21, and have their outer ends secured to the boiler wall as at 23 to form an air- and water-tight joint. It will be observed that the space 75 between the inner and outer shells of the boiler is sealed, and I prefer that the air within this space be withdrawn to form a vacuum insulation for the interior of the boiler.

The outer wall 10 of the boiler extends 80 beyond the end thereof provided with the openings 20 for a short distance as at 16 forming a flange receiving a false end 18 having a door 19 through which access may be had to the end wall proper of the boiler. 85

Heating units 25 of less length than the tubes 22 are provided, each embodying a central, preferably tubular, stiffening core 26 provided adjacent the ends thereof with transversely extending anchor pins 27, the 90 ends of which are disposed externally of the outer face of the stiffening medium. This stiffening core is surrounded by a suitable heat resistant material 28 such as porcelain. At its inner end the porcelain is provided with an enlargement 29 preferably conformed to the shape of the inner end of the tube 22. Extending outwardly from the side walls of the porcelain casing are radial flanges 30 arranged at spaced intervals and one of the flanges being disposed at the outer end of the porcelain casing. These flanges are provided adjacent the surface of the casing 28 proper with transverse openings 30^a for a purpose presently to appear. 95 100 105

Extending longitudinally of the porcelain casing is a bore 31 having its end opening through the face of the enlargement 29 at the inner end of the casing. Inter- 110

mediate the flanges 30 the casing is externally spirally grooved as indicated at 32 for the reception of a resistance element 33 preferably formed of spirally formed 5 chrome wire. Arranged at the outer end of the heat resisting element 25 is an insulating end plate 34 spaced from and secured to the flange 30 at the outer end by means of bolts 35 or the like and having its 10 outer face substantially flush with the outer end of the tube. Intermediate the outer face of the flange and the end plate 34 is disposed a layer 36 of electrical and heat insulating material of a compressible nature such as asbestos.

Extending through the plate 34 and the layer 36 are terminal connections 37, one of which communicates with the bore 30^a formed in the end flange 30 and the other of 20 which communicates with the longitudinal bore 31 of the porcelain casing 28. It will, of course, be understood that a conductor is connected with the inner end of the resistance coil 33 and extends through the bore 31 25 for connection with one of the terminals and that the outer end of the coil is connected with the other terminal to complete the circuit. Through the extended portion 16 of the outer wall 10 extend insulated conductors 38 which are connected with the terminals 37 in the conventional manner.

It will be understood that by reason of the construction hereinbefore described in event of the destruction of any of the heating units the same may be readily removed by opening the door 19, disconnecting the same, and withdrawing the unit 25 as a whole from its tube 22, when it may be repaired or replaced as it is found necessary.

40 By reason of the spacing of the tubes 22, the water is enabled to circulate therebetween for heating, and, due to the fact that not only are the contents of the boiler heat insulated from the action of currents of air 45 passing about the boiler, but the exposed ends of the heating units 25 themselves, are, likewise, insulated by the layer 36, a minimum amount of heat loss is encountered.

50 It will be obvious that by reason of the facility with which the heating units may be handled, and the fact that the heat insulation in my device is not limited merely to the boiler but is extended to the heating 55 units themselves or the exposed portions thereof, my device is particularly well adapted for use and, that, while the construction hereinbefore set forth is that construction which is preferred and which I

60 have found most efficient in use, it will be obvious that many minor changes could be made therein without in any manner departing from the spirit of my invention. I accordingly do not limit myself to this

specific structure hereinbefore set forth, except as so limited by the subjoined claims. 65

Having described my invention, what I claim is:

1. An electrical boiler comprising inner and outer shells arranged in spaced relation, 70 a series of spaced openings formed in one end wall of the boiler through said inner and outer shells, tubes within the boiler having their inner ends closed, said tubes extending through said openings, said tubes 75 being secured to said inner and outer shells at the sides of the opening through which they extend to form a fluid-tight joint, the space intermediate said inner and outer walls forming a heat insulation for the interior of the boiler, electrical heating units disposed within said tubes, the outer shell of said boiler projecting beyond the end thereof provided with the tube receiving openings and being adapted for the reception 80 of a false end and a door formed in said false end and providing access to the exposed ends of said electrical heating units.

2. The combination with a tube having 90 one end closed, of an electrical heating unit disposed within the tube, comprising an inner rigid core provided at the ends thereof with transverse pins extending beyond the walls of the core and forming anchors, a 95 body portion of heat resistant nonconducting material disposed about said inner core and provided at spaced intervals with outstanding portions forming flanges engaging the inner wall of said tube, a spiral groove 100 formed in the outer surface of said insulating material intermediate said flanges and an electrical resistance element disposed within said spiral groove.

3. The combination with a tube having 105 one end closed, of an electrical heating unit disposed within the tube, comprising an inner rigid core provided at the ends thereof with transverse pins extending beyond the walls of the core and forming anchors, a 110 body portion of heat resistant nonconducting material disposed about said inner core and provided at spaced intervals with outstanding portions forming flanges engaging the inner wall of said tube, a spiral groove 115 formed in the outer surface of said insulating material intermediate said flanges and an electrical resistance element disposed within said spiral groove, said flanges having openings formed therein through which said resistance element extends. 120

4. The combination with a tube having one end closed, of an electrical heating unit disposed within the tube, comprising an inner rigid core provided at the ends thereof with transverse pins extending beyond the walls of the core and forming anchors, a 125 body portion of heat resistant nonconducting

material disposed about said inner core and provided at spaced intervals with outstanding portions forming flanges engaging the inner wall of said tube, a spiral groove 5 formed in the outer surface of said insulating material intermediate said flanges and an electrical resistance element disposed within said spiral groove, a plate secured to the outer end of said heating unit and having its outer face flush with the end of said tube, a heat insulating member disposed intermediate said plate and the end of said unit and binding posts carried by said plate and connected with the ends of said resistance element.

5. An electrical boiler having the usual side and end walls and having a series of spaced openings formed in one end wall thereof, tubes within the boiler having their 10 inner ends closed, said tubes extending through said openings, said tubes being secured to said end at the sides of the opening through which they extend to form a fluid-tight joint, electrical heating units disposed 15 within said tubes, a plate secured to and spaced from the outer ends of each of said units, and a layer of heat and electrical insulating material disposed intermediate said plates and the outer ends of said heating units.

6. An electrical boiler having the usual side and end walls and having a series of spaced openings formed in one wall thereof, tubes within the boiler having their inner 35 ends closed, said tubes extending through said openings, said tubes being secured to said end wall at the sides of the opening through which they extend to form a fluid-tight joint, electrical heating units disposed within said tubes, a plate secured to and 40 spaced from the outer ends of each of said units, and having its outer end substantially flush with the outer end of the tube in which the heating unit is disposed, and a layer of compressible heat and electrical insulating 45 material disposed intermediate said plates and the outer ends of said heating units.

7. An electrical boiler having the usual side and end walls, a series of spaced openings formed in one end wall of the boiler, 50 tubes within the boiler having their inner ends closed, said tubes extending through said openings and electrical heating units disposed within said tubes and having their outer ends exposed, said outer ends being 55 heat insulated from the body portion of the heating units.

In testimony whereof I hereunto affix my signature.

LEONARD R. BRUNSWICK.
